US0D1025796S

(12) **United States Design Patent** (10) **Patent No.:** **US D1,025,796 S**
(45) **Date of Patent:** **** May 7, 2024**

(54) **WRIST WATCH**

(71) Applicant: **Shenzhen Amazwear Technology CO., LTD.**, Shenzhen (CN)

(72) Inventor: **Xianghua Wu**, Wuhan (CN)

(73) Assignee: **Shenzhen Amazwear Technology CO., LTD.**, Shenzhen (CN)

(**) Term: **15 Years**

(21) Appl. No.: **29/918,222**

(22) Filed: **Nov. 27, 2023**

(51) **LOC (14) Cl.** **10-02**

(52) **U.S. Cl.**

USPC **D10/38; D14/344**

(58) **Field of Classification Search**

USPC D10/30-39, 128, 132; D14/250, 344, D14/345, 440; D11/3, 5
CPC A45C 11/10; A45C 11/12; G04B 37/005; G04B 37/0058; G04B 37/084; G04B 37/087

(57) **CLAIM**

The ornamental design for a wrist watch, as shown and described.

DESCRIPTION

FIG. 1 is a front, right and top perspective view of a wrist watch, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 of FIG. 1 thereof; and,

FIG. 10 is an enlarged view of portion 10 of FIG. 1 thereof. The dot-dash broken lines depict the boundaries of the enlargements that form no part of the claimed design.

1 Claim, 10 Drawing Sheets
